UNITED STATES PATENT OFFICE

116,831

DESIGN FOR A TUCKED FABRIC

Emil Prazak, Jr., Elizabeth, N. J.

Application May 31, 1939, Serial No. 85,273

Term of patent 14 years

To all whom it may concern:

Be it known that I, Emil Prazak, Jr., a citizen of the United States, residing in Elizabeth, county of Union and State of New Jersey, have invented a new, original, and ornamental Design for Tucked Fabric, of which the following is a specification, reference being had to the accompanying drawing, forming part thereof.

In said drawing, Fig. 1 is a plan view of the tucked fabric showing my design; Fig. 2 is a perspective view; and Figs. 3 and 4 are respectively enlarged fragmentary transverse sectional views, taken on the respective lines 3—3 and 4—4 in Fig. 1 thereof.

I claim:

The ornamental design for tucked fabric, as shown.
